US00D776987S

(12) **United States Design Patent** (10) **Patent No.:** **US D776,987 S**
Repac (45) **Date of Patent:** **** Jan. 24, 2017**

(54) **FOOD CUTTING DEVICE**

(71) Applicant: **Genius GmbH**, Limburg (DE)

(72) Inventor: **Cedomir Repac**, Brechen (DE)

(73) Assignee: **GENIUS GMBH**, Limburg (DE)

(**) Term: **14 Years**

(21) Appl. No.: **29/524,872**

(22) Filed: **Apr. 24, 2015**

Related U.S. Application Data

(62) Division of application No. 29/402,255, filed on Sep. 22, 2011, now Pat. No. Des. 730,704.

(57) **CLAIM**

The ornamental design for a food cutting device, as shown and described.

DESCRIPTION

FIG. 1 is a top front right perspective view of a food cutting device showing my new design;

FIG. 2 is a right side elevational view thereof;

FIG. 3 is a left side elevational view thereof;

FIG. 4 is a front elevational view thereof;

FIG. 5 is a rear elevational view thereof;

FIG. 6 is a top plan top view thereof; and,

FIG. 7 is a bottom plan view thereof.

The broken lines shown in FIGS. 1-7 represent portions of the food cutting device that form no part of the claimed design.

1 Claim, 5 Drawing Sheets
